UNITED STATES PATENT OFFICE

SAMUEL LISH, OF WOODMERE, NEW YORK

DESIGN FOR A LADY'S HAT

Application filed May 15, 1933. Serial No. 48,125. Term of patent 7 years.

To all whom it may concern:

Be it known that I, SAMUEL LISH, a citizen of the United States, and a resident of Woodmere, in the county of Nassau, and State of New York, have invented a new, original, and ornamental Design for Ladies' Hats, of which the following is a specification, reference being had to the accompanying drawing, forming a part thereof, the single figure of which is a perspective view of a lady's hat embodying my new design. The lacing securing the top to the body of the hat extends entirely around the crown of the hat.

I claim:

The ornamental design for a lady's hat, substantially as shown and described.

SAMUEL LISH.
